UNITED STATES PATENT OFFICE.

ADRIAN FRANCIS SYKES, OF NEW BARNET, ENGLAND.

ELECTRICAL RELAY.

1,150,316.

Specification of Letters Patent. Patented Aug. 17, 1915.

Application filed June 3, 1915. Serial No. 32,003.

To all whom it may concern:

Be it known that I, ADRIAN FRANCIS SYKES, a subject of the King of Great Britain, residing at Lorne Villa, New Barnet, 5 Herts, England, have invented a new and useful Electrical Relay, of which the following is a specification.

This invention relates to electrical relays of the microphone type and is especially applicable for enabling speech waves to vary the powerful electric currents required for wireless telephony. The invention is, however, capable of being adapted to various uses and the appliances used in carrying it 15 into effect may be varied very widely.

According to my invention I control the current in an electric circuit by the addition to a stream of liquid which forms part of the circuit of varying quantities of an impurity or conductivity changer.

For the sake of clearness I will herein-after speak of the liquid as water and of the impurity as soda, meaning caustic soda in solution, though it is obvious that other 25 liquids and other impurities which will change the conductivity of the liquid may be employed.

The soda is supplied in varying quantities to a conduit through which is rapidly 30 flowing a stream of water. In consequence the conductivity of the various sections of water is varied, and if electrodes connected in a circuit be immersed in the water a little beyond the point where the soda enters, the 35 current in the circuit will be correspondingly varied. The distance of the electrodes from the point where the soda is introduced should be such as to give the soda sufficient but not too much time to diffuse through 40 the water. The electrodes may also be arranged opposite one another so that the resistance of the water in a transverse direction is utilized, or one may be placed beyond the other, in which case the longitudinal 45 resistance is the controlling factor.

My invention is illustrated by the accompanying drawings, Figure 1 being a sectional elevation, Fig. 2 a side view, Fig. 3 a part plan and Fig. 4 an end view. Fig. 5 50 is an enlarged view of the nozzle and Figs. 6 and 7 enlarged views of the conduit.

1 is a reservoir of soda supplied by a pipe 2. In the bottom of this reservoir is a circular hole surrounded by a knife edge 3 55 into which fits a rubber band or washer 4

surrounding the coned upper end of a brass tube 5 connected by an arm 6 to a diaphragm mounted in a sound-box 7 similar to the sound-box of a gramophone. At the upper end of the tube is a plate 8 having in it a sharp edged orifice. The reservoir and sound-box are carried by an arm 9 mounted on a pivot 10 at the top of a column 11 and provided with a depending part 12 held by a spring 13 against the point of an adjusting screw 14 which works in a lug 15 on the column. The arm carries a glass tube 16 which screens the jet and also a glass plate 17 through which the entry of the jet into the stream can be viewed without risk 70 of the soda splashing up into the eyes.

18 is a reservoir to which water is supplied under pressure; its top is closed by a cover 19 clamped down onto an insulating washer 20 which has at one point a rectangular channel 21 formed in it. In this channel is secured an obstruction or baffle 22 which splits the stream of water so as to form a cavity 23 therein. Beneath this cavity a hole 24 is bored in the bed of the channel so that, as the jet 25 passes through the cavity 23 and impinges on the downstream edge of the hole, part is diverted as shown in Fig. 6 and spreading out on the floor of the channel mingles with the stream while the rest falls down through the hole and runs to waste. The channel beyond the hole is formed of blocks 26 and side plates 27 all of insulating material. Below the blocks 26 are upper and lower plates 28, 29 which act 80 as electrodes being in electrical connection with binding screws 30, 31. The stream issuing from the end of the channel passes into a waste pipe 32. I have found that good results can be obtained with a stream 95 and jet having a velocity of 100 feet per second.

What I claim is:—

1. The combination of a stream of liquid forming part of an electric circuit, means 100 for introducing a conductivity changer into the stream and means for varying the quantity of conductivity changer thus introduced.

2. The combination of a stream of liquid forming part of an electric circuit, a jet of 105 conductivity changer and means for varying the proportion of the jet which enters the stream.

3. The combination of a source of electricity, a conduit, means for causing liquid 110

2 to flow through the conduit, electrodes connected to the source of electricity and in contact with the liquid, an aperture in the conduit, a jet of conductivity changer 5 adapted to enter the aperture, means for dividing the jet and means for varying the direction of the jet.

4. The combination of a source of electricity, a conduit, means for causing liquid 10 to flow through the conduit, electrodes connected to the source of electricity and in contact with the liquid, an aperture in the conduit, a vibratable diaphragm, a nozzle connected thereto, means for forcing through 15 the nozzle a jet of conductivity changer

toward the aperture and means for dividing the jet.

5. The combination of a source of electricity, a conduit, means for causing liquid 20 to flow through the conduit, electrodes connected to the source of electricity and in contact with the liquid, an aperture in the conduit, an obstruction in the conduit adapted to form a cavity in the liquid as it passes the aperture, a vibratable diaphragm, 25 a nozzle connected thereto, means for forcing through the nozzle a jet of conductivity changer toward the aperture and means for dividing the jet.

ADRIAN FRANCIS SYKES.
